UNITED STATES PATENT OFFICE.

EDWARD M. MOLLER, OF JERSEY CITY, NEW JERSEY.

ELECTRIC-CIRCUIT BREAKER.

1,391,966.

Specification of Letters Patent. Patented Sept. 27, 1921.

Application filed August 28, 1919. Serial No. 320,508.

To all whom it may concern:

Be it known that I, EDWARD M. MOLLER, a citizen of the United States, residing at Jersey City, in the county of Hudson and State of New Jersey, have invented certain new and useful Improvements in Electric-Circuit Breakers; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

This invention relates, generally, to improvements in circuit-breakers; and, the present invention has reference, more particularly, to that class of circuit-breakers for use upon trolley or electric railway cars.

The present invention has for its principal objects to provide a simply-constructed tripping-mechanism in which a magnetically controlled tripping mechanism is released when an excess charge of electricity passes into and through the assembled devices and parts of the device or apparatus, thereby furnishing protection against too heavy overloads or grounds, and short circuits which may occur in the car-equipment.

Other objects of the present invention are simplicity of construction of the mechanism; readiness of installation of the apparatus between the trolley-cable and the controller, the apparatus being light in weight, and being of high capacity and most efficient in its operation.

Still other objects of the present invention not at this time more particularly enumerated will be clearly understood from the following detailed description of the present invention.

With the various objects of the present invention in view, the said invention consists, primarily, in the novel car circuit breaker hereinafter more fully set forth; and, the present invention consists, furthermore, in the novel arrangements and combinations of the various devices and parts, as well as in the details of the construction of the said parts, all of which will be more fully described in the following specification and then finally embodied in the clauses of the claims which are appended to and which form an essential part of the said specification.

The invention is clearly illustrated in the accompanying drawings, in which:

Figure 1 is a plan or top view of the circuit-breaker embodying the principles of the present invention, the box or casing in which the mechanism is housed being represented in horizontal section; and Fig. 2 is a vertical sectional representation of the same, said section being represented as taken on line 2-2 in said Fig. 1, looking in the direction of the arrow *x*.

Fig. 3 is a similar sectional representation of the mechanism, said section being taken on line 3-3 in said Fig. 1, looking in the direction of the arrow *y*, the upper member of the box or casing, however, being omitted from said view.

Fig. 4 is a plan or top view of the circuit-breaking mechanism, showing the several parts thereof in their relative position, when the circuit is broken, said view being made on a slightly reduced scale, with the box or casing-members omitted from said view; and Fig. 5 is a detail vertical sectional representation and elevation of certain parts of the mechanism, represented as being taken on line 5-5 in said Fig. 1.

Fig. 6 is a plan view of the lower box or casing member; with the mechanism removed therefrom; and Fig. 7 is a longitudinal vertical section of the same, said section being taken on line 7-7 in said Fig. 6.

Fig. 8 is a bottom view of the upper box or casing-member; Fig. 9 is a side elevation of the same, looking in the direction of the arrow *z* in said Fig. 8; and Fig. 10 is a transverse vertical section of the same, said section being taken on line 10-10 in said Fig. 9.

Fig. 11 is a plan view of the arcing box or element employed with the mechanism; and Fig. 12 is an elevation of the same, looking in the direction of the arrow *u* in said Fig. 11.

Fig. 13 is a plan view of the overload or blow-out coil of the circuit-breaker, the upper member of said coil being omitted from said view; and Fig. 14 is a view of the said coil, partly represented in elevation and partly shown in vertical section.

Similar characters of reference are employed in all of the said above described views, to indicate corresponding parts.

Referring now to the several figures of the drawings, the reference-character 1 indicates the lower box or casing member of the

apparatus, the same being of any suitable configuration, comprising a top 2 and bounding side-walls 3 and end-walls 4, all mounted upon a closing base-plate 5, substantially as shown more particularly in Fig. 5 of the drawings, and the various members of the said box being made, preferably, of a material which is a non-conductor of electricity, or being suitably insulated so as not to 10 act as an electrical conductor. Suitably mounted above the top 2 of said lower box or casing-member 1 is an upper box or casing-member 6, corresponding in its general configuration to that of the said lower box 15 or casing-member 1, said upper box or casing-member comprising a top 7 and bounding side-walls 8 and end-walls 9, the said box being also made, preferably, of a material which is a non-conductor of electricity, 20 or being suitably insulated so as not to act as an electrical conductor. As shown, the said lower box or casing-member 1 is provided with suitably disposed ears or lugs 10 having holes or perforations 11 for the 25 attachment of the circuit-breaker in the desired location upon a car, or other place of location.

Similarly, within the interior of the upper box or casing-member 6, the latter is 30 provided with suitably disposed lugs, as 12, formed with internally screw-threaded receiving sockets 13 for the reception of the screw-threaded shanks of tightening studs or bolts 14 which are inserted into and 35 through properly located holes or perforations 15 in the top 2 of the lower box or casing-member 1 for properly securing the two members 1 and 6 together in operative relation, as will be clearly evident. In one 40 of its side-walls 8, the upper box or casing-member 6 is provided with suitably disposed openings, as 16 and 17, and in its opposite side-wall the said box or casing-member 6 has an opening 18, the purposes of 45 which will hereinafter be more fully set forth. The said upper box or casing-member 6 is also provided with a laterally extending partition 19 of the same material of which the box or member 6 is made, said 50 partition having an opening 20. To secure the base-plate 5 to said lower box or casing-member 1, the latter is provided with suitably disposed lugs, as 21, formed with internally screw-threaded sockets, as 22, for 55 the reception of the screw-threaded shanks of studs or screws 23, which are inserted into and through correspondingly located holes or perforations 24 in said base-plate 5, as indicated more particularly in Figs. 60 6 and 7 of the drawings.

The said upper box or casing-member 6 is also formed in one of its end-walls 9 with an opening, as 25, see Figs. 1 and 2 of the drawings, into and through which extends and projects, as shown in said Fig. 65 2, a suitably formed arcing-box or element 26, the purpose and construction of which will hereinafter be more fully described. Other studs or screws 27 may be used with the top-plate 2 of the lower box or casing-member 1, said screws 27 being inserted through holes or perforations 28 in said top-plate 2, and the screw-threaded shanks of said screws 27 being screwed into the internally screw-threaded receiving sockets 29 70 with which the partition 19 is provided. Referring now more particularly to Figs. 2, 3, 13 and 14 of the drawings, it will be seen, that disposed against the lower surface of said top-plate 2 is a layer of insulating material 29, and secured against the latter, by means of a bolt or screw 30, is a magnetic field-pole-piece or element 31 of soft iron, 80 said pole-piece or element having a downwardly extending portion 32 terminating, 85 near the base-plate 5 and extending longitudinally within the lower box or casing-member 1, in a carrier-member 33. Suitably secured upon the free end-portion of said carrier-member, by means of a screw 34 or 90 in any other suitable manner, is an upwardly projecting stem or rod 35 of metal, said stem or rod extending into and through a properly located hole or opening 36 in the top-plate 2, and being provided upon its 95 upper part, which is located within the upper box or casing-member 6, with an enlargement, as 37, formed with a screw-threaded receiving socket 38, for the purposes to be presently more fully described. 100 Surrounding that portion of the stem or rod 35, within the lower box or casing-member 1, and resting upon the carrier-member 33, is a tubular core 39 of soft-metal, and concentric with this core is a coil-spool, as 105 40, said spool being made of fiber or other insulating material. The overload or blow-out coil carried by said spool, consists of layers of flat copper 41, alternating with disks or layers 42 of cement paper, or the like, and 43 and 44 indicate the respective end terminals of the copper coil, said terminals being respectively provided with holes or perforations 45 and 46, in alignment vertically with correspondingly located holes or perforations 47 and 48 in the top-plate 2. Mounted upon the upper surface of said top-plate, and located within the upper box or casing-member 6, are a pair of cable-receiving and clamping elements, as 49 and 50, see Figs. 1, 2 and 3 of the drawings, the said clamping elements being secured in place by means of screws 51 and 52, respectively, which are screwed into the screw-threaded holes 53 and 54 with 115 120 which the top-plate 2 is provided, the cable-clamping jaws of the respective clamping elements 51 and 52 being, respectively, further provided with binding or clamping screws or bolts 55 and 56. Extending down- 125 130

wardly from the respective clamping elements 51 and 52, and projecting into and through the respective holes or perforations 47 and 48 in the top-plate 2 are contact-lugs 5 or studs 57 and 58, the lug or stud 57 being fitted in the hole or perforation 45 of the copper coil-terminal 43 and the lug or contact-stud 58 being fitted into the hole or perforation 46 of the copper coil-terminal 10 44, and the parts being securely fastened in their assembled relation by the usual arrangement of nuts, as 59 upon the said contact-lugs or studs 57 and 58, as will be clearly evident from an inspection of the 15 drawings.

Referring now more particularly to Fig. 2 of the drawings, it will be seen, that there is mounted upon the upper end-portion of the enlargement 37 of the previously-mentioned stem or post 35, a disk or plate 60, said disk or plate being held in place by a screw 61 which is screwed into the receiving socket 38, as indicated in dotted outline in said figure. Suitably mounted upon the 25 upper surface of said top-plate 2, by means of screws 62, or other suitable fastening means, is a plate 63, preferably formed with a reinforcing rib 64, and a pair of upwardly extending members 65 and 66, respectively 30 formed with bearing-positions 67 and 68. The said plate 63 is also provided with a suitably disposed hole or perforation 69 through which the rod or stem 35 projects, with the enlargement 37 of said rod or stem 35 resting directly upon said plate, in the manner indicated in Fig. 2 of the drawings. Oscillatorily disposed upon the enlargement 37 of the rod or stem 35 is the hub 70 of what is known as the switch-arm, said hub 40 having an arm 71 extending therefrom, said arm being provided at its free end with a bifurcated member 72, carrying a pin 73 with a roller 74 mounted upon said pin. At right angles to said arm 71, or approximately so, are a pair of other arms, as 75, located one above the other, said arms 75 having angularly disposed perforated end-members, as 76, carrying a pin 77. Pivotally mounted upon this pin 77 is a contact- 45 lever or member, as 78, provided at one end with a clamping element 79, between the clamping members of which is disposed, and securely clamped by means of a tightening bolt or screw 80, the one end-portion of 50 a copper series wire or cable 81, the other end-portion of the latter being securely clamped between the clamping members of the previously mentioned overload and blow-out coil-terminal 49. The clamping 55 element 79 of said lever or member 78 is also provided with a perforated portion 82 to which is attached the one end-portion of a coiled spring 83, said spring having its other end-portion secured to a perforated 60 lug 84 extending from the member 66 of the

plate 63. Upon its opposite end, the said contact-lever or member 78 is provided with a post-like portion or extension, as 85, formed with an abutting off-set 86, and seated against said post 85 and its off-set 86, 70 and secured in its position, by means of a bolt or screw 87, is a copper contact-establishing member 88, having a contact-tip 89 the surface-portion 90 of which is suitably curved or chamfered to provide a gradual 75 breaking surface and to prevent excessive arcing, as will hereinafter be more fully set forth. Secured to said contact-establishing member, by means of the bolt or screw 87, and resting against the back of the contact- 80 tip 89 is an angular arcing horn or deflector, as 91. Secured upon the upper surface of the top-plate 2, in suitable location, by means of screws 92, or in any other suitable manner, is a bar-like member or post 93, 85 carrying a clamping element 94, between the clamping member of which is securely clamped by means of a tightening bolt or screw 95, the end-portion of a leading-in wire or cable 96, leading from the usual 90 trolley-wheel.

This clamping element 94 is also formed with an abutting offset 97, and seated against said element 94 and its off-set 97, and secured in its position, by means of a 95 bolt or screw 98, is another contact-establishing member 99, having a contact-tip 100, the surface-portion 101 of which is also suitably curved or chamfered, which under normal initial conditions is electrically in contact with the contacting surface 90 of the contact-tip 89. Secured to said contact-establishing member 99, by means of the bolt or screw 98, and resting against the back of the contact-tip 100, is an angular arcing 105 horn or deflector, as 102.

As shown in said Fig. 2 of the drawings, the said contact-tips 89 and 100, as well as the arcing horns 91 and 102, project into the open end-portion 103 of the previously-mentioned arcing box 26, located in the end-wall 9 of the upper box or casing-member 6, the said box comprising a bottom-member 104, a top-member 105, and intermediate side-walls 106 and 107, to which said members 104 and 105 are secured by means of screws 108. As shown in Fig. 11 of the drawings, the said arcing-box 26 is usually provided with a receiving socket 109 into which is adapted to be fitted a stud or post, 110, connected with and extending from a lug or projection 111 with which the box or casing-member 6 is provided, substantially as illustrated in Figs. 8, 9 and 10, the purpose being to properly locate and hold 115 the said arcing box 26 in position. Located above the top-member 105 of said arcing box 26 is a magnetic field pole-piece or block 112 having an arm 113 the end-portion of 120 which extends along the inner surface of the 125 130

top 7 and through the partition 19, as shown in Fig. 10, the said partition being cast around the said arm 113, so as to securely hold the same in place. The block 112 is 5 usually secured to the arm 113 by means of rivets 114, although the said parts may be otherwise connected.

Extending upwardly from the previously-mentioned plate 63 are a pair of posts 115 and 116, on one of which, as 115, is mounted the hub-portion 117 of a pawl made in the manner of a bell-crank, said pawl comprising an arm 118 formed with an off-set 119 with which the roller 73 of the arm 71, 10 under normal initial conditions is in holding engagement. The arm 118 is also provided with a perforated lug 120, or other suitable means, to which is secured the one end of a tension spring 121, said spring 15 having its other end secured to a perforated lug 122 extending from the hub-portion 123 of a handle-lever 124, as shown in Figs. 1 and 4 of the drawings, the hub 123 of said lever being mounted upon the enlargement 20 25 30 35 40 45 50 55 60 65 ping arm 125 and causing a sufficient pivotal movement of the previously mentioned bell-crank which throws the retaining offset 119 out of its holding engagement with the roller 73 of the arm 71, as indicated in Fig. 4. Simultaneously, the tension spring 68 exerts its pull, so that the several arms 72, 75 and 78 assume the positions indicated in said Fig. 4, with the electric circuit interrupted or broken by the disengaged contact-tips 89 and 100, as will be clearly evident. To again set the parts of the apparatus, the handle-lever 124 is moved from the position shown in Fig. 4 to that illustrated in Fig. 1, the corresponding movement of the perforated lug 122 causing the spring 121 to exert a pull upon the arm 118, and resulting once more in the locked engagement of said arm with the roller 73 of the arm 71.

When it is desired to manually operate the mechanism for the purpose of interrupting or breaking the electric circuit, the handle-lever 124 is moved in the direction of the arrow *w*, see Fig. 1, thereby causing a stud or projection 151 on said handle-lever to ride against the incline or angular surface 153 of a projecting member 152 extending from the side-edge of the arm 118, thus also actuating the bell-crank, and causing the various parts to assume the positions indicated in said Fig. 4 of the drawings.

From an inspection of Fig. 2 of the drawings, it will be seen, that the magnetic pole-pieces 31 and 112 provide a magnetic field across the gap formed by the separated contact-tips 89 and 100 and across the space between the walls 104 and 105 of the blow-out box 26, whereby the arcing produced by the separating contact-tips and the generated gases will be forced by magnetic blow-out, through said box, and from the opening of the same, outside of the upper box or casing-member 6.

Referring again to said Fig. 2, the direction of the lines of magnetic force are across the gap between the walls 104 and 105, through the pole-piece or block 112, through the arm 113, across the air-space between the end-portion of said arm 113 and the tripping armature 131, through the latter, through the plate 60 and the stem or rod 35, through the pole-piece 31 and the top 2 into the wall 104.

Of course I am aware that changes may be made in the general arrangements and combinations of the various devices and parts, as well as in the details of the construction of the said parts without departing from the scope of the present invention as set forth in the foregoing specification, and as defined in the clauses of the claims which are appended to the said specification. Hence, I do not limit my present invention to the exact arrangements and combinations

of the said devices and parts as described in the said specification, nor do I confine myself to the exact details of the construction of the said parts, as illustrated in the accompanying drawings.

70

I claim:—

1. In an overload circuit-breaker, in combination with an overload coil, and a pair of terminal-clamps with which the respective terminals of the coil are connected, a magnetic core connected with said overload coil, a switch-arm oscillatorily mounted upon said core, a spring-controlled contact-lever connected with said switch-arm, a contact-tip carried by said switch-arm, a fixed contact-tip with which said first-mentioned contact-tip is normally in contact, a clamping element carried by said contact-lever, an electrical series-connection between said clamping element and one of said terminal clamps, and a tripping means for releasing said contact-lever and breaking the electrical contact between said contact-tips.

2. In an overload circuit-breaker, in combination with an overload coil, and a pair of terminal clamps with which the respective terminals of the coil are connected, a magnetic core connected with said overload coil, a switch-arm oscillatorily mounted upon said core, a spring-controlled contact-lever, a means of pivotal connection between said contact-lever and said switch-arm, a contact-tip carried by said switch-arm, a fixed contact-tip with which said first-mentioned contact-tip is normally in contact, a clamping element carried by said contact-lever, an electrical series-connection between said clamping element and one of said terminal clamps, and a tripping means for releasing said contact-lever and breaking the electrical contact between said contact-tips.

3. In an overload circuit-breaker, in combination with an overload coil, and a pair of terminal-clamps with which the respective terminals of the coil are connected, a magnetic core connected with said overload coil, a switch-arm oscillatorily mounted upon said core, a spring-controlled contact-lever connected with said switch-arm, a contact-tip carried by said switch-arm, a fixed contact-tip with which said first-mentioned contact-tip is normally in contact, a clamping element carried by said contact-lever, an electrical series-connection between said clamping element and one of said terminal clamps, and a tripping means for releasing said contact-lever and breaking the electrical contact between said contact-tips, consisting of a pivotally mounted tripping-armature adapted to be attracted by the core of said overload coil, a releasing means normally in engagement with said switch-arm, and means between said releasing means and the tripping-armature for actuating said releasing means.

130

4. In an overload circuit-breaker, in combination with an overload coil, and a pair of terminal clamps with which the respective terminals of the coil are connected, a magnetic core connected with said overload coil, a switch-arm oscillatorily mounted upon said core, a spring-controlled contact-lever, a means of pivotal connection between said contact-lever and said switch-arm, a contact-tip carried by said switch-arm, a fixed contact-tip with which said first-mentioned contact-tip is normally in contact, a clamping element carried by said contact-lever, an electrical series-connection between said 10 clamping element and one of said terminal clamps, and a tripping means for releasing said contact-lever and breaking the electrical contact between said contact-tips, consisting of a pivotally mounted tripping-armature adapted to be attracted by the core of said overload coil, a releasing means normally in engagement with said switch-arm, and means between said releasing means and the tripping-armature for actuating said releasing means.

5. In an overload circuit-breaker, in combination with an overload coil, and a pair of terminal-clamps with which the respective terminals of the coil are connected, a magnetic core connected with said overload coil, a switch-arm oscillatorily mounted upon said core, a spring-controlled contact-lever connected with said switch-arm, a contact-tip carried by said switch-arm, a fixed contact-tip with which said first-mentioned contact-tip is normally in contact, a clamping element carried by said contact-lever, an electrical series-connection between said clamping element and one of said terminal clamps, and a tripping means for releasing said contact-lever and breaking the electrical contact between said contact-tips, consisting of a pivotally mounted tripping-armature adapted to be attracted by the core of said overload coil, an auxiliary arm connected with and extending from said switch-arm, a pivotally disposed and spring-controlled bell-crank-pawl having one member in engagement with said auxiliary arm, and means between the other member of said pawl and the tripping-armature for actuating said pawl.

6. In an overload circuit-breaker, in combination with an overload coil, and a pair of terminal clamps with which the respective terminals of the coil are connected, a magnetic core connected with said overload coil, a switch-arm oscillatorily mounted upon said core, a spring-controlled contact-lever, a means of pivotal connection between said contact-lever and said switch-arm, a contact-tip carried by said switch-arm, a fixed contact-tip with which said first-mentioned contact-tip is normally in contact, a clamping element carried by said contact-lever, an

electrical series-connection between said clamping element and one of said terminal clamps, and a tripping means for releasing said contact-lever and breaking the electrical contact between said contact-tips, consisting of a pivotally mounted tripping-armature adapted to be attracted by the core of said overload coil, an auxiliary arm connected with and extending from said switch-arm, a pivotally disposed and spring-controlled bell-crank-pawl having one member in engagement with said auxiliary arm, and means between the other member of said pawl and the tripping-armature for actuating said pawl.

7. In an overload circuit-breaker, in combination with an overload coil, and a pair of terminal-clamps with which the respective terminals of the coil are connected, a magnetic core connected with said overload coil, a switch-arm oscillatorily mounted upon said core, a spring-controlled contact-lever connected with said switch-arm, a contact-tip carried by said switch-arm, a fixed contact-tip with which said first-mentioned contact-tip is normally in contact, a clamping element carried by said contact-lever, an electrical series-connection between said clamping element and one of said terminal clamps, and a tripping means for releasing said contact-lever and breaking the electrical contact between said contact-tips, consisting of a pivotally mounted tripping-armature adapted to be attracted by the core of said overload coil, an auxiliary arm connected with and extending from said switch-arm, a pivotally disposed and spring-controlled bell-crank-pawl having one member in engagement with said auxiliary arm, and means between the other member of said pawl and the tripping-armature for actuating said pawl, comprising a slidable tripping rod, a collar mounted upon said rod for engagement with the last-mentioned member of said pawl, a crank-extension carried by said tripping-armature, and a means of pivotal connection between said crank-extension and said tripping rod.

8. In an overload circuit-breaker, in combination with an overload coil, and a pair of terminal clamps with which the respective terminals of the coil are connected, a magnetic core connected with said overload coil, a switch-arm oscillatorily mounted upon said core, a spring-controlled contact-lever, a means of pivotal connection between said contact-lever and said switch-arm, a contact-tip carried by said switch-arm, a fixed contact-tip with which said first-mentioned contact-tip is normally in contact, a clamping element carried by said contact-lever, an electrical series-connection between said clamping element and one of said terminal clamps, and a tripping means for releasing said contact-lever and breaking the electrical

- contact between said contact-tips, consisting of a pivotally mounted tripping-armature adapted to be attracted by the core of said overload coil, an auxiliary arm connected 5 with and extending from said switch-arm, a pivotally disposed and spring-controlled bell-crank-pawl having one member in engagement with said auxiliary arm, and means between the other member of said 10 pawl and the tripping-armature for actuating said pawl, comprising a slidable tripping rod, a collar mounted upon said rod for engagement with the last-mentioned member of said pawl, a crank-extension carried by said tripping-armature, and a means of pivotal connection between said crank-extension and said tripping rod.
9. In an overload circuit-breaker, in combination with an overload coil, and a pair 20 of terminal clamps with which the respective terminals of the coil are connected, a magnetic core connected with said overload coil, a supporting plate having an opening into and through which a portion of said core 25 projects, a bearing-member upon said plate, a perforated lug extending from one of said bearing-members, a rod-receiving guide-post also upon said plate, a handle-lever having a hub-portion oscillatorily mounted 30 upon the core-portion above said plate, a perforated lug extending from said hub-portion, a switch-arm also oscillatorily mounted upon said core-portion, a contact-lever, a means of pivotal connection between 35 said contact-lever and said switch-arm, a contact-tip carried by said switch-arm, a fixed contact-tip with which said first-mentioned contact-tip is normally in contact, a clamping 40 element carried by said contact-lever an electrical series-connection between said clamping element and one of said terminal clamps, a coiled spring attached at one end to said contact-lever and at its other end to 45 the perforated lug extending from one of the bearing-members of said plate, a tripping-armature pivotally mounted between the bearing-members of said plate, an auxiliary arm connected with and extending 50 from said switch-arm, a bell-crank-pawl pivotally mounted upon said plate, a coiled spring attached at one end to the perforated lug of said handle-lever and at its other end with one of the members of said pawl for 55 forcing said member in engagement with said auxiliary arm, a tripping rod slidably disposed in the rod-receiving guide-post of said plate, a collar mounted upon said rod for engagement with the other member of 60 said pawl, a crank-extension carried by said tripping-armature, and a means of pivotal connection between said crank-extension and said tripping rod.
- 40 11. In an overload circuit-breaker, a casing having a partition-wall arranged to provide two compartments, said partition-wall having an opening, one of said compartments providing a blow-out chamber, and the end-wall of said casing forming part of said 65 chamber being likewise provided with an opening, combined with a circuit-breaking mechanism having a portion thereof extending through the opening in said partition-wall, an arcing-box located in said blow-out 70 chamber, said box having open end-portions, one of said end-portions projecting from the opening in said end-wall of the casing, and the said circuit-breaking mechanism being provided with separable contact-tips located within said arcing-box.
- 45 12. In an overload circuit-breaker, a casing having a partition-wall arranged to provide two compartments, said partition-wall having an opening, one of said compartments providing a blow-out chamber, and the end-wall of said casing forming part of 75 said chamber being likewise provided with an opening, combined with a circuit-breaking mechanism having a portion extending 80
- 50 10. In an overload circuit-breaker, in combination with an overload coil, and a pair of terminal clamps with which the respective terminals of the coil are connected, a magnetic core connected with said overload coil, a supporting plate having an opening into 85
- 55
- 60
- 65

- through the opening in said partition-wall, an arcing-box located in said blow-out chamber, said box having open end-portions, one of said end-portions projecting from the 5 opening in said end-wall of the casing, a pair of separable contact-tips located within said arcing-box, and a deflector-element extending from each contact-tip toward the opening in said arcing-box.

10 13. In an overload circuit-breaker, a lower box-member and an upper box-member, said lower member having a top providing a base for the upper box-member, said upper box-member having a partition-wall arranged to provide two compartments, said partition-wall having an opening, one of said compartments providing a blow-out chamber, and the end-wall of said upper box-member forming part of said blow-out chamber being likewise provided with an opening, a magnetic field-element within said lower box-member, and an overload coil mounted upon said field-element, a second magnetic field-member located within the blow-out 15 chamber of said upper box-member, combined with a circuit-breaking mechanism located within said upper box-member having a portion extending through the opening in said partition-wall, and provided with 20 separable contact-tips located in said blow-out chamber.

16. In an overload circuit-breaker, a lower box-member and an upper box-member, said lower member having a top providing a base for the upper box-member, said upper box-member having a partition-wall arranged to provide two compartments, said partition-wall having an opening, one of said compartments providing a blow-out chamber, and the end-wall of said upper box-member forming part of said blow-out chamber being likewise provided with an opening, a magnetic field-element within said lower box-member, and an overload coil mounted upon said field-element, a second magnetic field-member located within the blow-out 25 chamber of said upper box-member, combined with a circuit-breaking mechanism located within said upper box-member having a portion extending through the opening in said partition-wall, a pair of contact-tips located in said blow-out chamber, and a deflector-element extending from each contact-tip toward the opening in the end-wall of said upper box-member.

17. In an overload circuit-breaker, a lower box-member and an upper box-member, said lower member having a top providing a base for the upper box-member, said upper box-member having a partition-wall arranged to provide two compartments, said partition-wall having an opening, one of said compartments providing a blow-out chamber, and the end-wall of said upper box-member forming part of said blow-out chamber being likewise provided with an opening, a magnetic field-element within said lower box-member, and an overload coil mounted upon said field-element, a second magnetic field-member located within the blow-out 30 chamber of said upper box-member, combined with a circuit-breaking mechanism located within said upper box-member having a portion extending through the opening in said partition-wall, an arcing-box located in said blow-out chamber, said box having open end-portions, one of said end-portions projecting from the opening in said end-wall of the upper box-member, a pair of separable contact-tips located within said arcing-box, and a deflector-element extending from each contact-tip toward the opening in said arcing-box.

18. In testimony that I claim the invention set forth above I have hereunto set my hand this 13 day of August, 1919.

EDWARD M. MOLLER.
